UNITED STATES PATENT OFFICE.

HENRY E. WARREN AND WILLIAM M. WHEILDON, OF ASHLAND, MASSACHUSETTS,
ASSIGNORS TO THE LOMBARD GOVERNOR COMPANY, OF ASHLAND, MASSACHUSETTS, A CORPORATION.

APPARATUS FOR TREATING METAL OBJECTS.

1,334,335.

specification of Letters Patent. Patented Mar. 23, 1920.

Application filed July 13, 1918. Serial No. 109,172.

To all whom it may concern:

Be it known that we, HENRY E. WARREN and WILLIAM M. WHEILDON, citizens of the United States, and residents of Ashland, in the county of Middlesex and State of Massachusetts, have invented an Improvement in Apparatus for Treating Metal Objects, of which the following description, in connection with the accompanying drawings, is a specification, like characters on the drawings representing like parts.

This invention relates to apparatus for providing objects with a cylindrical body portion and with a conical or curved end portion or nose, and more particularly for shaping metal objects, such as shell forgings.

In accordance with the present invention, apparatus is provided with which the shell blank or forging is first acted upon by a tool which is moved with relation to the work to form a conical or curved nose or end portion, and thereafter the work is moved with relation to the nose-forming tool and preferably to other tools to form a cylindrical body portion. The shell blank or forging may also have its body portion acted upon by one or more tools which cut the blank transversely or radially and determine the length of the shell.

These and other features of this invention will be pointed out in the claims at the end of this specification.

Figure 1 is a plan view of a machine embodying this invention.

Fig. 2, a side elevation of the machine shown in Fig. 1.

70

The work to be treated is herein shown as a shell forging or blank *a* (see Fig. 9), which has the general shape of the finished shell and is mounted on a spindle or arbor, which has provision for firmly gripping the blank 75 and which is mounted to rotate and to move axially.

In the present instance the spindle (see Fig. 11), is composed of a rear member 10 and a front member 12, which is detachably secured to the rear member as by screws 13 or otherwise.

The front member 12 of the spindle is made of the proper diameter to have the blank *a* slipped upon it, and the said blank 85 is firmly secured thereon by suitable means, herein shown as gripping jaws *c*, which are movable in radial openings in the member 12, by means of cam surfaces or cones 15 on a rod 16, which is located in the spindle and is extended through the rear head 17 of the hollow spindle member 10, and through a diaphragm 18 to which it is fastened as by the nut 19 (see Fig. 12). The rod 16 is moved in the direction of the arrow 20, Figs. 95 11 and 12, by fluid pressure admitted into the chamber 21 behind the diaphragm 18, and when so moved, the cones or cams 15 move the gripping jaws *c* outwardly, and cause their teeth 22 to bite into the inner 100 surface of the blank *a* and thus firmly secure the said blank on the front member 12 of the spindle. The jaws *c* are held against the cones 15 by springs 23 acting on keys or lugs 24, Fig. 14, which extend into slots 105 or ways in the spindle member 12, and serve

to guide the jaws in their movement. The springs 23 are located in suitable recesses or slots 25 in the circumference of the spindle member 12.

- 5 The jaw-actuating rod 16 is moved in the direction opposite to that indicated by the arrow 20 by a spring 27, located in the present instance in the rear member 10 of the spindle, and when so moved, the cones or cams 15 are moved so as to release the gripping jaws and permit the springs 23 to disengage the jaws from the blank and render the latter loose on the spindle and capable of being removed therefrom.
- 10 The chamber 21 is formed by the diaphragm 18 and a casing 28, which latter is secured to one end of a tube 29, (see Fig. 12) fastened at its other end to the head 17 of the spindle member 10.
- 15 The head 17 constitutes a piston, which is detachably secured as by screws 290 to the rear end of the spindle member 10, and said piston is made of larger diameter than said member 10 to form a differential piston within the cylinder 30 into which the spindle member 10 is extended. The cylinder 30 (see Fig. 11) is provided with a front portion 31 of the external diameter of the spindle member 10, and with a rear portion 25 of the external diameter of the piston 17, so as to form an annular chamber 32 in front of the piston, which chamber is provided with a fluid inlet 33 (see Fig. 15) for the admission of fluid pressure employed to return the piston and spindle as will be described, and the cylinder is further provided in its rear head 34, with a fluid inlet 35 for the admission of fluid pressure behind the piston 17, so as to move the latter and the spindle forward, as will be described.
- 30 The cylinder 30 is also provided near its rear end with a fluid outlet port 36, which communicates with a port or passage 37 in the cylinder head 34 and with which latter is connected an exhaust or outlet pipe 38.
- 35 The outlet port 36 is arranged away from the head 34 of the cylinder 30, so as to leave a film or cushion of fluid behind the piston 17, which prevents contact of the latter with the cylinder head. The cylinder 30 is supported by the frame 40 of the machine, and forms a bearing for the rear end of the spindle member 10, whose front end rotates 40 in a bearing 41 supported by the frame 40 of the machine. The bearings 30, 41, are spaced apart, and the spindle member 10 has fast on it between said bearings, a gear 42, which meshes with and is rotated by a long pinion 43 on a shaft 44, supported in bearings 45, 46, secured to or forming part 45 of the frame 40.
- 50 It will be seen that the spindle is capable of being rotated and also of being moved axially, and provision is made as will be

described, for rotating the spindle without axial movement, and for rotating it while it is being moved axially.

To facilitate description and to enable the operation of the machine to be readily understood, the rotary movement of the spindle may be disregarded and the spindle assumed to have a stationary position under one condition and to be movable axially under another condition.

In accordance with this invention, it is designed to form the conical curved nose 47 of the finished shell (see Fig. 1) while the spindle is in its stationary condition, by movement of a suitable tool with relation to the work and spindle, and when the conical nose has been formed or finished, to form the cylindrical body portion 48 of the shell, by movement of the spindle axially with relation to the nose-forming tool and preferably to additional tools which may be designated body portion tools.

Referring to Fig. 9, 50 represents a turning tool of usual or known construction, which is adjustably secured in a holder 51 secured to a carrier 52, movable about a center so as to cause the tool 50 to move in the arc of a circle and thereby impart a curved or conical shape to the front end or nose of the blank *a*.

The tool carrier 52 is preferably made as herein shown, and consists of a radius arm, which is pivoted to move in a substantially vertical plane and also in a horizontal plane.

The radius arm 52 has one end mounted on a horizontal pivot 53 (see Fig. 6), which is carried by a vertical pivot 54 mounted on the frame of the machine on one side of the path of movement of the spindle, and the said radius arm is made of sufficient length to extend across the machine and be connected with a bar 55, which is mounted to slide on the frame 40 of the machine on the opposite side of the path of movement of the spindle from the pivot 54.

The radius arm 52 is vertically pivoted to permit it to be turned up, so as to leave the spindle clear for putting on and taking off the work, and is horizontally pivoted to enable the tool 50 to be moved with relation to the work to form the curved nose.

The radius arm 52 is provided with an upwardly curved intermediate portion 56 (see Fig. 6), which affords clearance for the work on the spindle, when the radius arm is in its horizontal or operative position shown in Figs. 1, 2, 6 and 9.

The radius arm 52 may be connected with the sliding bar 55 by means of a block 58 (see Figs. 3, 9 and 10) pivoted to the bar 55 to move in a horizontal plane, and adapted to be straddled by lugs or ears 59 on the free end of the radius arm.

The nose-forming tool 50 may be moved to cut or turn off the work from the front

end of the blank *a* toward the body portion thereof, by fluid pressure admitted into a cylinder 60 (see Figs. 1, 2 and 9) supported by the framework, said cylinder having its 5 plunger or piston 61 attached to or forming part of the sliding bar 55.

Provision is made for arresting the movement of the nose-forming tool 50, when the latter reaches a position where the curvature of the nose, merges with the cylindrical body portion of the blank, and when the nose-forming tool 50 reaches this position, the said tool is available for use in turning off or shaping the body portion of the blank 10 to impart to the external surface of the latter a true cylindrical form or shape.

In the present instance the forward movement of the nose-forming tool is arrested by a stationary lug or stop 62 on the frame- 15 work of the machine (see Figs. 3, 9 and 10), which is engaged by the sliding bar 55.

The blanks *a* are made longer than it is desired the finished shells should be, and provision is made for cutting the blank radially or transversely, so as to remove the surplus rear portion of the blank and leave the finished shell of the desired length, and at the same time provide it with a substantially smooth rear end. For this purpose, preferably two cutters 64, 65, are employed (see 20 Figs. 9 and 16), which are located on opposite sides of the path of movement of the spindle, and are moved toward and from the spindle by fluid pressure admitted into the 25 cylinders 66, 67, supported by the framework of the machine and provided with differential pistons 68, 69, to the front ends of which the cutters or tools 64, 65, are detachably secured by bolts 70, and clamping plates 30 or bars 71 or otherwise.

The cylinders 66, 67, are radially disposed with relation to the spindle and have their front ends open, and are provided with slots 72, which extend longitudinally from the 45 open front ends for the passage of the cutting tools 64, 65. The cylinders 66, 67, are of like construction, and each is provided with a front portion of the external diameter of the front portion of its piston, and with 50 an enlarged rear portion of the external diameter of the enlarged rear end or head of the piston, so as to form an annular chamber 73 of materially smaller area than that of the cylinder in front of the piston head. 55 The chambers 73 of the cylinders 66, 67, are designed to be connected together and with the supply of fluid pressure, and the cylinders behind the pistons are connected together and with the supply of fluid pressure, 60 and also with the exhaust side of the system as will be described.

The tools 64, 65 may be designated the cutting off tools, and they are designed to act while the nose tool 50 is acting to shape the 65 nose of the shell, and inasmuch as the time

required to cut off the surplus portion of the blank *a* may be and usually is materially less than that required to trim the nose portion to the proper or desired size, and further as it is necessary that the cutting-off tools 70 should be disengaged from the work, when the latter is moved forward to enable the body portion of the blank to be trimmed, provision is made as will be described for insuring that the cutting-off tools are in 75 their inoperative or withdrawn position before the forward axial movement of the spindle and work begins.

After the nose blank has been shaped by the nose-tool 50, the latter is in its extreme 80 forward position represented in Figs. 1 and 3, and in position to cut the outer surface of the body portion of the blank, and said tool is now stationary because the radius arm or carrier 52 is stationary, inasmuch as the 85 slide 55 is held against the stop 62 by the fluid pressure in the cylinder 60 acting on the rear end of the piston 61. The nose tool 50 may be relied upon to trim or cut the body portion of the blank *a*, but it is preferred to 90 employ additional tools 75, 76, for this purpose, (see Figs. 1 and 9), which tools for sake of distinction may be termed the body cutting tools. The tools 75, 76, are secured to the carrier or radius arm 52 in such manner as to be inoperative on the nose of the blank; and so as to become operative on the body portion of the blank, when the nose tool has finished its work on the nose of the blank and is in its stationary position, represented in Fig. 3. The body cutting tools 75, 76, are also preferably secured to the tool carrier or radius arm 52, so as to cut on opposite sides of the body portion, and as the nose tool 50 and the body cutting tools 75, 100 76, are stationary while in their cutting position, the work or shell blank *a* is moved with relation to the said tools, which latter effect a straight cut or one parallel with the 105 axis of the spindle.

The cutting tools being in their operative position to cut the body portion of the blank, the spindle is now moved axially in a forward direction indicated by the arrow 78, Fig. 11.

This forward movement is effected by admitting fluid pressure into the cylinder 30 through the inlet pipe 35, so as to act on the full area of the piston 17.

On the forward movement of the spindle, 120 the blank *a* is fed past the body cutting tools 75, 76, and the nose tool 50, and the outer surface of the body portion of the blank is cut to a true circle concentric with the center of the spindle.

Provision is made for automatically controlling the forward axial movement of the spindle, and for starting this movement at or about the time the nose tool 50 reaches its stationary position.

To this end, a differential valve 80, 81, which is preferably made as shown in Fig. 17, has its stem or rod 82 extended outside of the valve casing 83, so as to be engaged by 5 the upper end of a lever 84 (see Fig. 3), which has its lower end connected by a link 85, with the lower end of a lever 86, whose upper end is extended into the path of movement of a stud or pin 87, which projects laterally from the radius arm 52.

The lever 84 may be connected with the valve stem 82, by extending its upper end into a slot 88 (see Fig. 17) in the enlarged end of the said stem, and the lower end of 15 the lever 84 may be movably connected with the link 85 for a purpose as will be described, by extending the threaded end 89 of the link 85 through a slot 90 in the lever 84 (see Fig. 4), and mounting a spring 91 between the 20 lever 84 and a nut or head 92 on the threaded end of the link, and providing the latter with nuts 93 on the other side of the lever 84.

The valve 80 of the differential valve is shown as a piston movable in a cylinder 94, 25 which is open at its opposite ends to connect the chambers 95, 96 in the valve casing 83, and the valve 81 is a disk valve of larger area than the piston valve 80 and operates with the outlet port of a chamber 30 97 in the valve casing 83, and controls communication between the chambers 97, 95.

The chamber 95 is connected with the spindle cylinder 30 by the outlet pipe 38. The chamber 96 is connected with the said 35 supply tank 103 by the pipe 101, and the chamber 97 in the present instance is connected by the pipe 102 with a cylinder 105 for a purpose as will be described. The pipes 38, 101 and valve casing 83 connect 40 the exhaust or outlet for the spindle cylinder 30 with the supply tank 103, and normally the valves 80, 81, are open, so as to afford a free communication between the rear end of the cylinder 30 and the supply tank 103, which contains oil or other fluid, and when 45 the valves 80, 81, are opened as described, the fluid admitted into the spindle cylinder 30 behind the piston 17, returns to the supply tank 103 through the port 36, passage 50 37, pipe 38, chamber 95 of valve casing 83, chamber 96 and pipe 101. A portion of the fluid in the chamber 95 can pass through the chamber 97 and pipe 102, which 55 may be connected with the pipe 101 if desired, or as herein shown with the cylinder 105 shown in Figs. 3 and 18, for a purpose as will be described.

The valves 80, 81, are normally opened by a spring 106 (see Fig. 3), which moves 60 the link 85 in the direction of arrow 107, so as to cause the nuts 93 to engage the lever 84 and turn it so as to move the valve 81 away from its seat and to move the piston or valve 80 out of its cylinder 94.

65 The differential valve remains in this open

position while the nose of the blank *a* is being shaped, and at or about the time the nose tool-operating piston 61 approaches the end of its forward stroke, the pin 87 strikes the lever 86 and through the link 85 turns 70 the lever 84 so as to close the differential valve 80, 81, thereby closing the outlet from the spindle cylinder 30 and causing the fluid pressure admitted into the said cylinder through the pipe 35, to become effective 75 upon the piston 17 to move the spindle and the work thereon forward or in the direction of arrow 78. On this forward movement of the spindle, the body portion of the shell blank *a* is moved past the stationary 80 tools 50, 75, 76, which turn the outer surface of the body portion into true cylindrical shape or form with the spindle as a center.

It will be understood, that the spindle is rotated when it has a stationary relation 85 to the nose-forming tool 50, and also when it has an axially movable relation to the body-turning tools 50, 75, 76.

Provision is also made for boring the nose of the shell blank and for cutting off 90 or finishing the end of the nose, when the shell blank is moved axially forward, and to this end a boring tool 110 and a squaring or finishing tool 112 (see Figs. 1 and 9) are secured to a carrier, which is shown as a 95 lever 113 pivoted to the framework 40 at one side of the same near its front end.

The lever 113 in its operative position shown, in Figs. 1, 5 and 9 occupies an upwardly inclined position, and is adapted 100 to be locked in this position by a pin 114, which is extended through lugs 115 on the cylinder 60 and through the lever 113. The lever 113 has its free end of a width substantially equal to the space between the 105 lugs 115, so that the said lever may be firmly backed up while the boring and squaring tools 110, 112, are in operation.

It is desirable that when the spindle has reached the end of its forward stroke, it 110 should remain stationary so far as axial movement is concerned, for a limited time, before it begins its return stroke, for two purposes, one of which is to permit the end of the nose to be smoothed off, and the other 115 is to enable the radius arm 52 to be lifted so as to remove the tools away from the work and thereby prevent the latter being scored or injured by the said tools on the return movement of the spindle.

The spindle is maintained in a relatively stationary position at the end of its forward stroke, by manipulating the differential valve as will now be described. The stem 82 of the differential valve has an 125 extension 108 (see Figs. 3 and 17), which projects outside of the valve casing 83 and is adapted to be engaged by an adjustable stop, shown as a threaded rod or bolt 109, carried by a cross head 110 mounted on the 130

tube 29 so as to move with the spindle. At or near the end of the forward stroke of the spindle, the stop 109 engages the extension 108 of the valve stem 82, and moves the valves 80, 81, so as to open the disk valve 81 slightly while keeping the valve 80 closed. Under these conditions, the fluid under pressure passes from the chamber 95 behind the disk valve 81, and as soon as the disk valve 81 is opened sufficiently to pass through the pipe 102 an amount of fluid substantially equal to that flowing into the spindle cylinder 30 behind the piston 17 therein, the differential valve is balanced, and the spindle remains stationary with relation to axial movement, and while the spindle is stationary, the tool 112 squares off or smooths the end of the nose 47 of the shell.

In the present instance, the fluid pressure which passes behind the valve 81 flows through the pipe 102 into the cylinder 105 (see Fig. 18) containing a piston 121, whose rod 122 engages a collar 123 on an extension 124 of the radius arm 52. As the pressure accumulates in the cylinder 105, the piston 121 is moved, and its rod 122 lifts the radius arm 52 until the piston 121 reaches the end of its upstroke, at which time the tools 50, 75, 76, are clear of the work. On the upward movement of the radius arm, the pin 87 is disengaged from the lever 86, which allows the spring 106 to move the link 85 in the direction of the arrow 107, Fig. 3, and through the nuts 93 turn the lever 84 so as to open wide the differential valve 80, 81, thereby connecting the spindle cylinder 30 with the supply tank 103, and permitting the spindle to be returned to its starting position by the fluid pressure in the chamber 32 of said cylinder.

At or about the time the lifting piston 121 reaches the end of its upstroke, a collar or hub 125 on the piston rod engages a crank or arm 126 on a rock-shaft 127, and rocks the latter so as to open a valve 128 (see Fig. 5) in the exhaust or outlet pipe 129 for the cylinder 60, thereby allowing the piston 61 to be returned by fluid pressure admitted through the pipe 132, Fig. 3, into an annular chamber in front of the rear end of the piston 61, similar to the chamber 32 of the spindle cylinder 30.

The spring 91 coöperates with the lever 84 and the head 92 on the link 85 to form a practically positive connection, yet one which permits the differential valve 80, 81 to be moved by the stop 109, without moving the link 85. For by reference to Fig. 3, it will be seen that when the radius arm 52 is in its forward stationary position, the pin 87 is in engagement with the lever 86, and therefore the link 85 is prevented from being moved by the lever 84, but the latter is permitted to be moved by the valve stem

82, by reason of the spring 91 yielding in response to movement of the lever 84.

The cutting off tools 64, 65, are moved toward the spindle by the fluid pressure admitted into the cylinders 66, 67, so as to act on the full area of the enlarged heads 140, 141 of the pistons 68, 69, which cylinders are connected in multiple with a pressure supply pipe 142 by branch pipes 143, 144 (see Fig. 16) and by connecting the cylinders in multiple both tools are caused to do an equal amount of work.

The cylinders 66, 67 have their fluid outlet or return pipes 145, 146 connected with a common return pipe 147, which leads to the supply tank 103. The pistons 68, 69, are moved on their return stroke by fluid pressure admitted into the annular chambers 73 in the cylinders 66, 67, and said chambers are connected in multiple with a pressure pipe 148 by branch pipes 149, 150 (see Fig. 1). The fluid pressure becomes effective to move the pistons 68, 69 on their forward or working stroke, when a valve 151 (see Fig. 7) in the exhaust or return pipe 147 is closed. The exhaust valve 151 is conventionally shown in Fig. 7, as it may be of any suitable construction, and said valve is normally held open by a spring 152 encircling its stem 153.

Provision is made for manually closing the exhaust valve 151 and also for automatically opening the same by the cutting-off piston. The exhaust valve 151 may be manually closed as herein shown by means of a lever 155, which has one arm encircling the valve stem 153 between a nut 156 and collar 157, and which is connected with a crank 158 on the rock-shaft 127, by collar 160 and nut 161 on a rod 162, which is extended through the lower end of the said lever.

By reference to Fig. 7, it will be seen that when the rock-shaft 127 is turned, so as to move the rod 162 in the direction of the arrow 163, the nut 161 moves the lower end of the lever 155 in the same direction, and acting on the collar 157 moves the valve stem 153 so as to close the exhaust valve 151, which action permits the fluid pressure to accumulate in the pipe 147 and hold the exhaust valve in its closed position, and also to accumulate in the cylinders 66, 67, and move the pistons 68, 69, toward the spindle.

Provision is made for positively opening the exhaust valve 151, when the cutting-off tools have completed their work, and for this purpose, the piston 68 has secured to its head 140 (see Figs. 16 and 19), a rod 165, which is extended through the head of the cylinder 66 and through the upper arm of the lever 155 and provided with a nut 166, which is adjusted on said rod so as to engage the upper arm of said lever, and turn the latter on its pivot and move the

valve stem 153 so as to initially open the exhaust valve 151 against the pressure and permit the spring 152 to complete the opening of said valve substantially in an instant, thereby preventing further forward movement of the cutting-off tools, which are then moved back to their starting position by the fluid pressure in the chambers 73 of the cylinders 66, 67. The rock-shaft 127 also controls the exhaust valve 128 for the cylinder 60, and to this end, said rock-shaft is provided with a crank or arm 170 (see Fig. 5), which straddles the stem 171 of the exhaust valve 128 between a nut 172 and a collar 173, the latter being acted upon by the spring 174 to normally hold the valve 128 open.

When the rock-shaft 127 is rocked by means of the handle 175 in the direction of arrow 176, Fig. 5, the crank or arm 170 closes the exhaust valve 128 and the same movement closes the exhaust valve 151.

From the above description, it will be seen that the fluid pressure becomes effective to 25 axially move the spindle forward and to move the pistons 61, 68 and 69 forward when the return circuits from the cylinders of these parts are closed.

The return circuits referred to, are normally open and provision is made for a constant circulation of the oil or other fluid from the supply tank 103 through the various cylinders referred to and back to the tank. To this end, a suitable pump, herein 35 shown as a rotary pump 180 (see Fig. 2), is driven from a main shaft 181 by a belt 182, passed about pulleys 183, 184 on the shaft 181 and the pump shaft 185.

The pump 180 takes oil or other liquid 40 from the supply tank 103 through a pipe 186, strainer 187 and pipe 188, and discharges it through the pipe 33 into the chamber 32 of the spindle cylinder 30, from which it passes through the outlet pipe 190 (see 45 Figs. 3 and 15) into coupling 191. The T-coupling 191 is connected by pipe 195 with a pipe 196, which forms a main for a plurality of branch pipes 132, 197, 198 and 35. The pipe 132 leads to the annular chamber 50 within the cylinder 60. The pipe 198 has a coupling 199, from which leads the pressure supply pipe 142 for the cut-off cylinders 66, 67, and the supply pipe 148 for the chambers 73 of said cylinders. The pipe 142 is provided with a throttle valve, preferably a needle valve 200, by which the rate of flow into the cylinders 66, 67, behind the pistons may be regulated. The pipe 197 is provided with a similar needle valve 201, and the pipe 55 35 is provided with a needle valve 202, which regulates the flow of fluid into the cylinder 60 and into the spindle cylinder 30 respectively.

The pipe 148 serves as a supply for the

chamber 21 provided with the diaphragm 65 18, which operates the gripping jaws *c*. To this end, the pipe 148 has connected with it a pipe 204, having its other end connected with a coupling 205, (see Figs. 1 and 12), which is attached to the stationary cross head 206. The coupling 205 has connected with it a pipe 207, which is extended into a larger bore or socket 208 in the end of the rod 16. The fluid admitted into the socket 208 passes through ports 209 into the chamber 21, wherein it acts on the diaphragm 18 to cause the gripping jaws to secure the work onto the spindle.

The pipe 204 is provided with a three-way valve 210, which is connected by the pipe 211 80 with the supply tank. When the valve 210 is turned into one position, fluid pressure is supplied to the diaphragm chamber 21, and in another position of the valve 210, the chamber 21 is connected with the tank 103 85 through the pipe 211.

The three-way valve 193 in one position connects the pipe 215 with the return pipe 101, through pipe 194 and in another position connects the pipe 192 with the pipe 215 90 (see Figs. 1, 3, and 20), which leads to a bearing 216 for the main shaft 181, and communicates with an annular groove 217 in said shaft, from which leads an axial passage 218 in said shaft, said passage at its 95 opposite end leading to a chamber 219 in a hydraulic clutch, (see Fig. 20), which controls rotation of the spindle.

The hydraulic clutch is mounted on the shaft 181 and is provided with a diaphragm 100 220, which moves a clutch member 221 into engagement with a coöperating member 222 to render a pinion 223 fast on the shaft 181. The pinion 223 is fast to the clutch member 222 to rotate therewith, and the clutch member 221 is keyed to the shaft 181 to rotate therewith and to slide thereon. The clutch member 221 is moved out of engagement with the member 222 by a spring 225. The pinion 223 meshes with and drives a gear 110 226 fast on the shaft 44. The main shaft 181 is designed to be rotated continuously and is provided with a driving pulley 227.

The valve 193 controls the operation of the hydraulic clutch, and when the machine 115 is idle, the said valve connects the pipe 215 with the tank 103 through the pipes 194, 101. When it is desired to start the machine in operation, the valve 193 is turned to connect the pipe 215 with the pressure pipe 192, and 120 thereupon pressure is admitted into the chamber 219 of the clutch, which pressure forces the clutch member 221 into engagement with the clutch member 222, thereby starting rotation of the spindle.

While the cutting tools are acting on the work or blank *a*, they may be supplied with a cooling and lubricating solution, such as a

soapy solution, by means of a small rotary pump 280, (see Fig. 2), which may be driven by a belt 231 from the pump shaft 185.

While it is believed that the operation of the machine is clear from the above description, a brief description of the operation will now be given.

Assume that the machine is in position to receive the blank *a*. In this case, the spindle 10 is at the end of its return stroke as shown in Fig. 11.

The radius arm 52 is in a substantially upright position with its rear end resting on a projection 250 on the pivot 54, the lever 113 is thrown back, and the cutting-off tools 15 are in their withdrawn position. The blank *a* is now placed upon the spindle. The radius arm 52 is then lowered into the position shown in Fig. 9, and the nose tool 20 50 adjusted to the nose of the blank *a*. The lever 113 may be lowered at this time and locked by the pin 114. Fluid is circulated 25 by the pump 180, which is continuously driven from the main shaft 181. The operator 30 now turns the three-way valve 210 to connect the pipe 204 with the pipe 148, and thereby admit fluid pressure into the chamber 21, which acts on the diaphragm 18 and causes the gripping jaws to secure the 35 blank *a* to the spindle. The valve 193 is now turned to close the pipe 194 and connect the pipe 215 with the pressure pipe 192, so as to admit pressure into the chamber 219 of the hydraulic clutch and start rotation of the spindle and work.

The work is now ready for the nose-forming and the cutting-off operations. The operator having properly positioned the nose tool 50 by turning the radius arm on the pivot block 58, opens the needle valves 40 200, 201, and moves the handle 175 to turn the rock-shaft 127 and close the exhaust valves 151, 128. The circulation of fluid 45 through the cylinders 60, 66, and 67, is thus interrupted and pressure builds up in said cylinders, thereby moving the pistons 61, 68, 69, on their forward strokes. The piston 61 moves the radius arm 52 in the 50 arc of a circle with the pivot 54 as a center, until the sliding bar 55 meets the stop 62.

In the meantime, the cutters 64, 65 trim off the rear end of the blank *a*. As soon as the cutting-off pistons 68, 69, have reached the end of their forward stroke, the exhaust 55 valve 151 is automatically opened by the nut 166 and lever 155, and the pistons 68, 69, and the cutting-off tools 64, 65 are returned to their starting position.

The operator can manipulate the nose 60 tool 50 any desired number of times to make any desired number of cuts with the nose tool, by simply rocking the shaft 127 so as to open the exhaust valve 128, which permits the piston 61 to be returned to its starting

position by the pressure admitted into the 65 cylinder 60 through the pipe 132.

After the nose of the shell has been properly trimmed off, the radius arm 52 is held against the stop 62 by the pressure in the cylinder 60, and the nose tool 50 and body 70 tools 75, 76 are now stationary and in proper position to act on the body portion of the blank, which is now fed forward axially past said tools. The forward feed of the spindle and work is automatically 75 started by the pin 87 moving the lever 86, which through the link 85, spring 91 and lever 84 closes the differential valve 80, 81, and causes the fluid pressure to become effective on the piston 17 of the spindle. 80

The spindle is moved axially forward a sufficient distance to insure the body portion of the blank *a* being properly cut to a true circle with the spindle as a center, and also to bring the end of the nose into 85 operative relation to the boring tool 110 and the squaring tool 112. When the nose has been properly bored, the forward feed of the spindle and work is arrested by the stop 109 operating the differential valve so 90 as to balance the pressure upon the said valve, and as the spindle and work continue to rotate, the tool 112 smooths off and finishes the end of the nose before the spindle starts on its return stroke. 95

In the present machine, the pressure which passes behind the disk valve 81 passes to the cylinder 105, and acting on the piston 121, lifts the radius arm so that the tools 50, 75, 76 clear the work and prevent 100 the latter being scored or otherwise injured by the said tools on the return stroke of the spindle, which is effected by the differential valve 80, 81, being opened wide by the spring 106 as soon as the pin 87 is removed 105 from engagement with the lever 86. The radius arm 52 is then turned by the operator into its substantially vertical position, and the lever 113 is also turned back, which leaves the work accessible to be removed 110 from the spindle as soon as the valve 210 is turned to connect the pipe 204 with the pipe 211, and the valve 193 is turned to connect the pipe 215 with the pipe 194.

When the pipe 204 is connected with the 115 pipe 211, the fluid in the chamber 21 is forced back into the tank 103 by the spring 27, which latter moves the rod 16 so as to permit the gripping jaws to be disengaged from the work, and when the pipe 215 is 120 connected with the pipe 194, the spring 225 throws out the hydraulic clutch and stops rotation of the spindle.

Provision is made for regulating the 125 amount of fluid pressure in the system, and to this end a relief valve 260 (see Fig. 3) is connected with the T-coupling 191 and by pipe 261 with the tank 103.

In the present instance, the radius arm 52 is automatically lifted so as to have the tools clear the work before the spindle makes it return stroke, but it is not desired 5 to limit the invention in this respect, as this lifting movement of the radius arm may be effected manually, in which case the cylinder 105 may be omitted, and the pipe 102 connected with the tank 103 as indicated by the dotted lines in Fig. 3.

We have herein shown one construction 15 of machine embodying the invention, but it is not desired to limit the invention to the particular construction shown. The spindle cylinder 30 may be provided with an outlet pipe 300 for any air which may accumulate in the chamber 32.

Claims.

1. In combination, a work-holding spindle having an axial and a rotary movement, 20 a tool carrier mounted to move in the arc of a circle to cause a tool carried thereby to act on a portion of the work, and means for moving said spindle axially to move 25 the work with relation to said tool to cause the latter to act on another portion of the work substantially at the end of the circular movement of the tool carrier.

2. In combination, a work-holding spindle, means for rotating the same, a tool carrier extended transversely of the said spindle and pivoted at one end and having its other end movable longitudinally with relation to the work-holding spindle to cause 35 the tool to describe an arc in the direction of the length of said spindle, a piston operatively connected with said tool carrier to turn the latter on its pivot, and a cylinder for said piston.

40 3. In combination, a work-holding spindle, means for rotating it, a tool-carrier movable in the arc of a circle longitudinally of the work on said spindle while the latter is revolving in a fixed position, means for 45 moving said spindle longitudinally after it has been acted upon by the tool mounted on said tool carrier, a tool-operating piston movable transversely with relation to said spindle after the latter has been moved 50 longitudinally a predetermined distance, and a cylinder for said piston.

4. In combination, a work-holding spindle movable axially, a cylinder in which said spindle reciprocates, a differential valve 55 controlling the circulation of fluid through said cylinder, means for operating said valve to interrupt the circulation of fluid through said cylinder and thereby effect axial movement of said spindle in one direction, a tool carrier movable longitudinally with relation to said spindle and coöperating with said differential valve to operate the same and effect axial movement of 60 said spindle in one direction.

65 5. In a machine of the character described,

in combination, a work-holding spindle, a cylinder in which said spindle reciprocates and through which fluid is circulated, a tool carrier movable lengthwise of the work on said spindle, a piston for moving said 70 tool carrier, a cylinder for said piston and through which fluid is circulated, a piston movable transversely with relation to said spindle, a tool operated by the last-mentioned piston, a cylinder for the last-mentioned piston and through which fluid is circulated, and means for interrupting the circulation of fluid through said cylinders to cause the fluid pressure to become effective to move said pistons and spindle. 75

6. In combination, a work-holding spindle having an axial and a rotary movement, a cylinder in which said spindle rotates and moves axially, a valve controlling the axial movement of said spindle in one direction, 80 a tool to act on the work, a carrier for said tool movable toward said spindle, and mechanism operatively connected with said valve and actuated by said tool carrier to operate said valve to cause the spindle to move axi- 90

7. In combination, a work-holding spindle having an axial and a rotary movement, a cylinder in which said spindle rotates and moves axially, a valve controlling the axial 95 movement of said spindle in one direction, a tool to act on the work, a carrier for said tool movable toward said spindle, and mechanism operatively connected with said valve to move the latter. 100

8. In combination, a work-holding spindle having an axial and a rotary movement, a tool-carrier pivotally mounted to turn in the arc of a circle to cause a tool carried thereby to act on a portion of the work, and means for moving said spindle axially to move the work with relation to said tool. 105

9. In combination, a work-holding spindle having an axial and a rotary movement, a tool to act on said work and toward which 110 said spindle is moved axially, a carrier for said tool bodily movable into and out of the path of movement of said spindle, a piston operatively connected with said spindle, a cylinder in which said piston is moved axi- 115 ally and is rotated, fluid means for effecting axial movement of said piston and spindle, and means for rotating said piston and spindle while they are moving axially.

10. In combination, a work-holding spindle having an axial and a rotary movement, a cylinder in which said spindle reciprocates and through which fluid pressure is circulated, a valve controlling the circulation of fluid through said cylinder, a tool 125 carrier movable toward the work on said spindle and coöperating with said valve to effect the circulation of fluid and cause the spindle to be moved axially.

11. In combination, a work-holding spin- 130

idle having an axial and a rotary movement, a cylinder in which said spindle reciprocates and through which fluid pressure is circulated, a valve controlling the circulation of fluid through said cylinder, a tool to act on the work on said spindle and movable lengthwise of said spindle, and means movable with said tool for operating said valve to effect axial movement of the spindle.

10 12. In combination, a work-holding spindle having an axial and a rotary movement, means for effecting axial movement of said spindle in one direction, and a tool to act on the work on said spindle and movable toward said spindle and controlling the axial movement of the spindle toward the said tool.

13. In combination, a work-holding spindle, means for moving said spindle axially, and a tool movable with respect to the spindle to act on the work thereon and controlling axial movement of said spindle in one direction.

14. In combination, a work-holding spindle, means for moving said spindle axially, and a tool movable with respect to the spindle to act on the work thereon and con-

trolling axial movement of said spindle in opposite directions.

15. In combination, a work-holding spindle having an axial and a rotary movement, a cylinder in which said spindle reciprocates and through which fluid pressure is circulated, a valve controlling the circulation of fluid through said cylinder, and mechanism for operating said valve to interrupt the circulation and thereby move the piston axially, said mechanism having a yielding member to permit the valve to be opened to again establish the circulation.

16. In combination, a work-holding spindle having an axial and a rotary movement, a cylinder in which said spindle reciprocates and through which fluid pressure is circulated, a valve controlling circulation of the fluid through said cylinder, and a tool movable with relation to said spindle to act on the work thereon and controlling the operation of said valve.

In testimony whereof, we have signed our names to this specification.

HENRY E. WARREN.
WILLIAM M. WHEILDON.
